UNITED STATES PATENT OFFICE.

HENRY C. HART, OF DETROIT, MICHIGAN.

SPRING AIR-GUN.

SPECIFICATION forming part of Letters Patent No. 437,491, dated September 30, 1890.

Application filed May 12, 1890. Serial No. 351,504. (No model.)

To all whom it may concern:

Be it known that I, HENRY C. HART, of Detroit, in the county of Wayne and State of Michigan, have invented a new and useful Improvement in Spring Air-Guns, of which the following is a specification.

My invention consists in an improvement in spring air-guns, hereinafter fully described and claimed.

10 Figure 1 is a partial side elevation, partly in section, of a central portion of the gun; and Fig. 2 is a vertical central section through the end of the magazine and barrel and breech-block and forward end of the spring-chamber.

15 A represents the stock of the gun, usually made of wood.

B represents two similar castings secured together by the screw J, and serving as a 20 trigger-housing and to connect the spring-chamber with the stock of the gun, as more fully explained in my former application for patent.

Y represents the spring-chamber of the gun 25 secured at its forward end to a breech-block W and at its rear end to the housing B. D represents a coil-spring within said spring-chamber, its rear end resting against an abutment X.

30 E represents a piston-rod passing through spring D and connected with the forward end of said spring with an air-compressing piston and at the rear end with a washer F.

N represents a lever by which the spring D 35 is compressed.

G represents a rod, one end of which is connected with said washer F, and in my former application the connecting-rod corresponding to G was shown as bent and connected with 40 the operating-lever. Instead of that arrangement I have substituted the one herein shown by interposing between the connecting-rod G and the lever N a vibrating lever I, pivoted at one end on the screw J, and to the other end of 45 said lever the connecting-rod G is pivoted.

K represents a connecting-rod pivoted at the point L to the central lever I, and pivoted at its other end at the point M to an operating-lever N, which is pivoted at the point 50 O in a slot cut in the top of the stock A. By this arrangement I avoid a bend in the connecting-rod between the piston-rod and the operating-lever and transmit the power of the lever to the piston-rod more easily and 55 with less loss.

The other part of my invention relates to the carrier-block.

P represents a movable carrier-block moving in an aperture in the breech-block W, and provided with a spring Q, whose free end is 60 forked and engages with slots in the carrier-block P, as shown in my former application, and whose other end is held in a keeper R on the under side of the spring-chamber.

U represents a false barrel, similar to that 65 in my former application, containing a true barrel T and a magazine S, in which V represents a number of shot. The rear end of the magazine communicates with a hole in the breech-block W, in which the carrier-block P works, and this carrier-block is made of such length that, when it is drawn down by pulling down on the free end of the spring Q, the last shot in the magazine will roll into the aperture in which said carrier-block P 75 moves and will lie on the upper end of said carrier-block. When the spring Q is released, the carrier-block pushes said shot upward and lightly pinches the shot between its upper end and the upper surface of the 80 true barrel, as shown in Fig. 2, whereby said shot is prevented from rolling out of the gun by gravity or by shaking, but yet is left free to be discharged by a blast of compressed air from the spring-chamber Y.

85 What I claim as my invention, and desire to secure by Letters Patent, is—

1. In a spring air-gun, the combination, with an operating-spring and its piston-rod, of an operating-lever pivotally secured to the 90 stock, an intermediate lever pivoted to the gun, and two connecting-rods connecting said intermediate levers respectively with the piston-rod and the operating-lever, substantially as shown and described.

95 2. In a spring air-gun, the combination, with a true barrel and a magazine, of a movable carrier-block and an actuating-spring, whereby said carrier-block is adapted to transfer a ball from the magazine to the barrel 100 and pinches the shot between its upper end and the upper surface of the true barrel, substantially as shown and described.

HENRY C. HART.
